UNITED STATES PATENT OFFICE

2,551,880

STRAIGHT BEAM ADJUSTABLE JAW CLAMP

Bert T. Gressley, Cheney, Wash.

Application January 5, 1948, Serial No. 571

1 Claim. (Cl. 144—303)

1

This invention relates to new and useful improvements, and structural refinements in adjustable clamps, and the principal object of the invention is to provide a clamp of the character herein described, such as may be conveniently and effectively employed for supporting pouring forms in the formation of concrete curbs, walks, and similar structures.

The further object of the invention is to provide an adjustable clamp which, in addition to its primary purpose above outlined, may also be effectively employed for various other clamping purposes.

Another object of the invention is to provide an adjustable clamp which is simple in construction, which may be quickly and easily manipulated and which will not easily become damaged.

An additional object of the invention is to provide an adjustable clamp which will readily lend itself to economical manufacture and which is otherwise well adapted for the various purposes for which it may be used.

With the above more important objects in view, and such other objects as may become apparent as this specification proceeds, the invention consists essentially of the arrangement and construction of parts as illustrated in the accompanying drawings, in which:

Figure 1 is a side elevational view of the invention;

Figure 2 is an end view, taken in the direction of arrow 2 in Figure 1;

Figure 3 is a top plan view of the invention;

Figure 4 is a cross sectional view taken substantially in the plane of the line 4—4 in Figure 1; and

Figure 5 is the cross sectional view, taken substantially in the plane of the line 5—5 in Figure 1.

Like characters of reference are employed to designate like parts in the specification and throughout the several views.

Referring now to the accompanying drawings in detail, the invention consists of an adjustable clamp designated generally by the reference character 10, the same embodying in its construction a bar 11 having an I-shaped cross sectional configuration, as is best shown in Figure 5.

A pair of straps 12, 12' are welded or otherwise secured to the web 12 of the bar 11, these straps projecting beyond one end of the bar and carrying a pivot pin 13. The projecting portion of one of the straps (12') is enlarged to accommodate an arcuate slot 14.

A downwardly extending arm 15 is formed in

5

the upper end portion thereof with an I-shaped opening 16 to slidably accommodate the bar 11, that is to say, the arm 15 is slidable on the bar, as will be clearly apparent. If desired, the free end portion of the bar may be upturned so as to provide a stop 17, which will prevent the arm 15 from sliding off the bar.

A downwardly arcuated extension 18 is mounted on the aforementioned pivot pin 13, the extension 18 being equipped with a clamping screw 19 which slidably and adjustably engages the aforementioned slot 14 of the strap 12'.

The lower end portion of the extension 18 terminates in the forked extremity 20, between the arms of which a lever 21 is pivotally mounted by means of a pin 22.

Moreover, a U-shaped shoe or pad 23 is associated with the extension 18, this being accomplished by providing the shoe 23 with a pair of opposed slots 24 to slidably accommodate the pin 22.

The lever 21 terminates at the pivoted end thereof, with a cam-surfaced portion 25 which is frictionally engageable with the closed end portion 26 of the shoe 23, substantially as shown.

It will be apparent from the foregoing that by simply pressing the lever 21 in the direction of the arrow 27, the shoe 23 will be urged in the direction of the arrow 28, that is, toward the arm 15.

Finally, it should be explained that the arm 15 is provided with a suitable clamping screw 29, whereby the position of the arm may be set with respect to the bar 11, as desired.

When the invention is placed in use, the clamp may be applied to the work, such as for example, to two spaced forms for pouring concrete, this being effected by placing the arm 15 of the clamp adjacent one of the forms while the shoe or pad 23 is disposed adjacent the second form, as will be readily understood.

Needless to say, the distance between the shoe 23 and the arm 15 may be adjusted in accordance with the spacing of the two forms by simply loosening the screw 29 and sliding the arm 15 on the bar 11.

Needless to say, during this pre-adjusting procedure, the lever 21 should be in a substantially horizontal position, so that the shoe 23 may be slid as far as possible from the arm 15. However, after the pre-adjustment is completed, the lever 21 may be depressed, thereby urging the shoe 23 against the form, so that the form-clamping operation is effected.

The clamp may be quickly and easily removed

2

55

from the work, this being accomplished either by sliding the arm 15 toward the slot 17, or alternatively, by loosening the screw 19 and swinging the entire extension 18, together with the lever 21, upwardly, as indicated at 30. In either event, the shoe 23 should first be released by swinging the lever 21 to an elevated position, as will be clearly apparent.

It is believed that the advantages when using the invention will be clearly apparent from the foregoing disclosure and accordingly, further description thereof at this point is deemed unnecessary.

It is to be understood, however, that even though there is herein shown and described a preferred embodiment of the invention the same is susceptible to certain changes fully comprehended by the spirit of the invention as herein described and the scope of the appended claim.

Having described my invention, what is claimed as new is:

An adjustable clamp comprising a bar, a laterally projecting clamp member adjustable longitudinally on said bar and having a lateral work engaging surface, a downturned extension con- 25

nected to one end of the bar and swingably adjustable in the plane of said bar and said clamp member, a transverse pin on said extension, a cam on said pin, and a clamping shoe engaged by said cam and having a work engaging surface opposing the work engaging surface of said clamp member, said shoe being provided with a slot to slidably and swingably receive said pin, whereby the respective work engaging surfaces of the shoe and of said clamp member may be parallel notwithstanding adjustment of said extension relative to said bar.
